OR THE LIKE

Arthur W. Carlson, Muskegon, Mich., assignor to
E. H. Sheldon & Company, Muskegon, Mich.

Filed Sept. 30, 1974, Ser. No. 510,510

Term of patent 14 years

Int. Cl. D23—01

U.S. Cl. D23—32

FIG. 1 is a rear perspective view of a fixture for a laboratory table or the like showing my new design;

FIG. 2 is a front elevational view thereof;

FIG. 3 is a rear elevational view thereof;

FIG. 4 is a top plan view thereof; and

FIGS. 5 and 6 are side elevational views respectively thereof.

The fragmentary broken line representation of a laboratory table and the broken line representation of water cocks and gas jet in FIG. 1 are for purposes of illustration only.

I claim:

The ornamental design for a fixture for laboratory table or the like, as shown and described.
